UNITED STATES PATENT OFFICE

136,351

DESIGN FOR A COMBINED BOTTLE AND CAP

Paul M. E. Mayer, New York, N. Y.

Application July 2, 1943, Serial No. 110,589

Term of patent 14 years

To all whom it may concern:

Be it known that I, Paul M. E. Mayer, a citizen of no country, residing in the city of New York, in the county and State of New York, have invented a new, original, and ornamental Design for a Combined Bottle and Cap, of which the following is a specification, reference being had to the accompanying drawing, forming part thereof, wherein:

Fig. 1 is a top plan view of the combined bottle and cap showing my new design;

Fig. 2 is a front elevation thereof.

I claim:

The ornamental design for a combined bottle and cap, as shown.

PAUL M. E. MAYER.
